US0D1033433S

(12) **United States Design Patent** (10) **Patent No.:** **US D1,033,433 S**
(45) **Date of Patent:** **** Jul. 2, 2024**

(54) **COMPUTING DEVICE WITH TOUCHPAD DISPLAY SCREEN**

(71) Applicant: **Intel Corporation**, Santa Clara, CA (US)

(72) Inventors: **Aleksander Magi**, Portland, OR (US); **Duck Young Kong**, Beaverton, OR (US); **Mikko Makinen**, San Jose, CA (US); **Stan C. Woody**, Portland, OR (US)

(73) Assignee: **Intel Corporation**, Santa Clara, CA (US)

(**) Term: **15 Years**

(21) Appl. No.: **29/771,488**

(22) Filed: **Feb. 23, 2021**

Related U.S. Application Data

(63) Continuation of application No. 29/673,785, filed on Dec. 18, 2018, now Pat. No. Des. 914,021.

(57) **CLAIM**

The ornamental design for a computing device with touchpad display screen, as shown and described.

DESCRIPTION

FIG. 1 is a right, front perspective view of a computing device with touchpad display screen, showing our new design;

FIG. 2 is a front view thereof;

FIG. 3 is another right, front perspective view thereof, showing the touchpad display screen in an alternate display mode state with environmental graphics; and,

FIG. 4 is a front view thereof.

The broken lines showing the environmental graphical features of the display modes on the touchpad display screen for the computing device from no part of the claimed, while all other broken lines depict portions of the computing device with touchpad display screen that form no part of the claimed design.

1 Claim, 4 Drawing Sheets
